UNITED STATES PATENT OFFICE.

GILBERT C. WHITNEY, OF NEW YORK, N. Y.

TRAIN-INDICATION SYSTEM.

Application filed July 1, 1925. Serial No. 40,789.

This invention relates to train describers and train indicators in general wherein means are provided to indicate the position or describe the movement of a train on a railway track, and in particular, a novel means is disclosed for inexpensively determining conditions affecting the operation of an electrified railway system and also providing a means of communication between the train, at any time 5 from any point, and the customary tower or other quarters.

This present application is a continuation, in part, of my co-pending application, Serial No. 33,731, filed May 29, 1925, and my prior 15 Patent No. 1,596,222, issued August 17, 1926, for train indication system.

The general objects of this invention are; to provide a simple and inexpensive means whereby an indication as to whether an electrically propelled train, using the track rails for return of the propulsion current, is proceeding under electric motor power or is coasting; to provide a means of determination as to defective rails or defective bonding in the 20 propulsion return current system; and to incorporate the same into the system of my prior application, Serial No. 33,731, and my prior Patent No. 1,596,222, so that a single simple system will indicate the position of 25 the train; whether the train is moving or at rest and the direction if moving; as to whether the train is being electrically propelled or is coasting; as to the value and maintenance of the propulsion return current system; as to general operating efficiency of the 30 motorman; to locate all indication receiving apparatus inexpensively at one place or more, if desired, for a given territory; and to provide a means for the motorman to communicate to the tower, despatcher's office or other 35 selected station.

My invention, herein disclosed, is identically the same as disclosed in my prior Patent No. 1,596,222, hereinbefore referred to, 40 except that additional features inherent to said system, when installed on electrified railroads, are brought into effect.

In describing my invention I will refer to the accompanying drawings wherein Fig. 1 45 sets forth the indication system of my prior application to which has been added a third rail to conduct the electric power from the power house generator G to the electric motorized train on the track section; Fig. 2 is a 55 descriptive harmonic wave drawing showing the relations of the primary and secondary

currents in the field inductive coupling when only one A. C. current is flowing in the track circuit; Fig. 3 shows a typical magnetization curve well known in the electrical arts; Fig. 60 4 is a descriptive harmonic wave drawing showing the relation and influence of the different characteristics of the wave shapes of Fig. 2 when a direct current (propulsion return current) of different amounts is superposed on the A. C. indication current; and Fig. 5 is a descriptive wave drawing showing the relation and influence of the different characteristics of the wave shapes of Fig. 2 when an alternating current (propulsion return current) of different frequency is superposed on the A. C. indication current; all of 65 which figures will be referred to hereinafter.

The reference characters distinguishing the parts of Fig. 1 are the same as in my prior 70 patent, hereinbefore referred to.

Referring to Fig. 1, a track section is set apart by insulated track rail joints 8—the track rails of the section being identified by the reference characters 6 and 7. At one end 80 of said track section a transformer 9 is shown connected to track rails 6, 7, by means of track wires 10, 11, resistance 12 and fuse 13. Transformer 9 is the medium, when energized by means of wires 14, 15, from power wires 85 16, 17, connected to the source of energy alternator 18, by which appropriate current supply, when a train is not present, is transmitted over track rails 6, 7, to track wires, 19, 20, fuse 21, and resistance 22 to winding 23 90 of relay 24. Relay 24 is shown deenergized because, as illustrated, a train is present in the track section. Winding 25 of relay 24 receives energy by means of wires 26, 27, from power wires 16, 17, and thus far the whole 95 constitutes the well-known alternating current track circuit wherein most of the energy required for the operation of the track relay 24 is supplied locally and only a small part or activating current is transmitted over 100 the track rails. Also, in conventional manner, I have shown signal 32—33 controlled by contact 28 of track relay 24 and control wires 29, 30, and 31. The track and circuit and signal and circuit design outlined above is 105 intended simply as a structure and I make no claims of invention in connection therewith—it is shown only to provide a basis for suitably illustrating my invention. I have illustrated but one track section for the purpose of making the drawing as simple as possible but it will be understood that, in prac-

tice, a consecutive series of track sections similarly comprised would be used as required.

This invention consists in connecting the primary winding 35, of transmitter transformer (inductive coupling) 34, in multiple with resistance 12, as shown, and so that part of the current flowing to winding 23 of relay 24 passes through said winding 35. Inductively coupled to winding 35 is shown secondary winding 36 and the current induced therein is carried over transmission wires 37, 38, to the tower or other selected point and there energizes winding 40 of transformer 15 (inductive coupling) 39. Inductively coupled to winding 40 is shown secondary winding 41 and the current induced therein becomes available and is used for energizing indicator device lamp 42 or other similarly 20 appropriated means, as will be appreciated. When the track section is not occupied by a train, winding 23 and resistance 22 are included in series in the circuit receiving current which passes from transformer 9 and 25 through winding 35, but when a train enters the track section the wheels of the train, having negligible resistance, shunt out said winding and resistance and due thereto more current flows from transformer 9 via winding 35. The increased rate of current flow varies depending upon the position of said train in the track section, being lowest when the train is furthest distant from transformer 9, because of the resistance of the 30 track rails 6, 7, as will be appreciated. From the above it will be clear, that the current flow in the transmission circuit 37, 38, and consequently illumination of indicator lamp 42 will be least when said track section is not 35 occupied and will variably increase with the entrance onto and passage of the train along toward the transformer 9 end of the track section.

The rails 6 and 7 of the track section are 40 generally securely mounted on wooden ties to maintain the proper gauge relation and to serve as an insulating medium to insulate rails 6 and 7 one from the other and from the ground. Because of the fact that the 45 wooden ties are subjected to rain and other moisture their value as an insulator varies and due thereto it is customary to apply only low voltages for the regular energy supply to the track circuit.

50 It is the general custom to arrange the indicator lamps at a central point for a given territory which may be of considerable extent and, owing to the great number of circuits involved, economy demands that small wires be used in the transmission circuit and naturally only a small transmission current can be tolerated, otherwise the loss in transmission would not only be prohibitive but would otherwise interfere with the indication 55 as hereinafter pointed out. Starting then

with the necessarily low track circuit voltage I provide inductive coupling 34 to act as a step-up transformer to provide a higher transmission circuit voltage and the corresponding transmission current for indication 70 purposes is of the order of 0.015 ampere and less. Now, as is well-known, an indication lamp of high voltage and low wattage (one (1) watt and less) is not commercially possible because of the inability to provide a 75 filament which will heat on a current flow of the above mentioned order of 0.015 ampere and less and accordingly I provide receiver inductive coupling transformer 39 of the step-down type and wherein the resultant induced indicating current flow to lamp 42 is of the order of 0.080 to 0.350 ampere and at an operating voltage of from approximately one (1) volt to five (5) volts. Thus it will be evident that, in the use of transformer 39, 80 means have been provided to effect an indication on a very small transmitted power and with a minimum in the losses of transmission. A minimum in the losses of transmission is 85 important for the reason that the variation in current flow in the rail circuit, as between the train or car at several points within a given track section, is small and all efforts must be made to conserve the results of the variation, during transmission to the indication device. 90

I have previously shown that the train enters onto and proceeds over the track section and it will be understood that the train, represented by car-wheels 43-43^a, electrically connected by member 44, is equipped with propelling electric motor 45, a controller 46 for said motor and third rail sliding contact 47 which contact is in continuous contact with third rail 48. The propulsion current is supplied by generator G to the third rail 48 by means of wire 49 and the return circuit from the track rails is via wire 50 connected to track rail 7. It will be understood, that the bonds connecting the several track rails comprising track rail 7 of the track section are of suitably heavy design appropriate to the purpose. The operation of the train by motor power is simple: Controller 46 is moved into engagement with contact 46^a and current then flows from generator G via wire 49, 110 third rail 48, third rail sliding contact 47, thence via controller 46, now closed, motor 45 connecting member 44, car-wheels 43-43^a and returning thence over rails 6 and 7 to generator G via wire 50 and rotation of the 115 motor is produced resulting in movement of the train, as will be appreciated. The train operating means, just described, form no part of my invention, except that intermittent manual operation of controller 46 is involved in certain combinations to produce, 120 and producing various effects on the indication system by virtue of the current flowing via controller 46—and excepting also that the propulsion current may at times be com- 125 130

bined with signaling current to influence the indication system.

I have stated that the return of the propulsion current from the motor is via track rails 6 and 7 and it will be apparent that, since track rail 6 is separate from track rail 7, at the generator G end of the track section, all propulsion current flowing in track rail 6 must flow via the secondary circuit of transformer 9 which includes wires 10 and 11, fuse 13 and resistance 12 with winding 35 of my inductive coupling 34 in multiple with resistance 12.

From the foregoing it will be evident that, 15 the return propulsion current actually flows in the circuit with the alternating current from transformer 9 and both currents flow in the winding 35 of inductive coupling 34 and in amounts comparable to the conditions of 20 the circuits at any particular time.

In Fig. 2 I have shown a diagram illustrating a simple sine wave A of a twenty-five (25) cycle alternating current and representing the current used in the signaling and indication system and is to be understood, for the purposes of clearly describing my invention only, as being the current wave, of maximum value P , flowing in winding 35 of inductive coupling 34 when the track section is 25 in normal condition and not occupied by a train and when in this condition the induced current, wave B of maximum value Q , flowing in the transmission circuit 37, 38, which includes winding 36, is not sufficient to produce even a slight illumination of indicator lamp 42. Induced current wave B is shown 30 in time relation 90° later than primary current wave A, because of the fact that, as ordinarily designed, the power requirements 35 of my indicating device, lamp 42 or other appropriate means, is small and in no wise more than a fraction of the capacity of inductive coupling 34 so that the time relation of the induced current wave follows the induced no-load voltage wave, as is well known in the 40 design of induction apparatus but it will be understood that with a non-inductive indicating means coupled to inductive coupling 34 and of approximately the capacity thereof 45 the induced current wave would be in approximately the same time relation as primary current wave A. At the bottom of Fig. 50 2 I have shown, in full hatched order, the corresponding value of power in the transmission circuit and consequently the comparative value of induced current flow C to the indicating device lamp 42 when the track section is not occupied. Now, when the train enters the track section, as before explained, 55 and without electric power, the car-wheel 43-43a-44 short-circuiting track rails 6 and 7 produces a shunt on transformer 9 causing increased current to flow via winding 35 and for the condition when the car-wheel shunt is 60 at the exit end of the track section the corre-

sponding current waves are shown respectively AA of value PP and BB of value QQ and the comparative value of energy flow to indicating lamp device 42 at CC. It being understood, of course, that with the car-wheel 70 shunt at intermediate points in the track section the values would be synchronously correspondingly intermediate those just previously described. It will be understood, of course, that the increase in track circuit current flow via winding 35, when the track section becomes occupied, is reflected in the transmission circuit eventually to appear at the indication device, in accordance with the well-known laws of mutual induction and 80 because of change in the flux density in the magnetic circuit which change is wrought by the primary or track circuit current synchronously and automatically.

At this time I desire to point out that, 85 while, hereinbefore, I have explained that when the track section is not occupied the energy supply to the lamp 42 is not sufficient to produce even a slight illumination, I wish it to be understood distinctly that I may arrange to have the energy flow to the lamp, when the track section is not occupied, sufficient to cause the lamp filament to glow dimly or partially lighted and thereafter with synchronously progressively more illumination 95 as the section becomes occupied and the train proceeds, from left to right, therethrough.

It will be appreciated that track relay 24 is not essential to the operation of my indication system and therefore may be used or 100 omitted as desired.

I have explained that the progressive increase in illumination of lamp 42 is a synchronous indication of the movement of the train from left to right. The synchronous 105 indication of a train movement in the opposite direction would be shown by the lamp appearing with full illumination as the car-wheel shunt enters the section (from the right) and thereafter with synchronously 110 diminishing value as the car-wheel shunt proceeds through the section.

Resistance 12, shown in multiple with winding 35, in addition to performing the functions; of preventing the train being 115 a short circuit on transformer 9—of providing proper phase relation for the operation of relay 24—of permitting sufficient current to flow to the track rails for the regular operation of relay 24 independent of winding 120 35, which winding may become highly reactive due to an accidentally opened secondary circuit which includes winding 36—also serves, as hereinafter set forth, in connection with adjusting the effects and influences due 125 to the return propulsion current being superposed on the original alternating current used for the track circuiting and indication system. I also direct attention to the fact that an adjustable resistance (not shown) 130

may be used in series with the winding 35 for adapting a single inductive coupling design for use with variable weights of track rails and under various practical conditions 5 arising with variable voltages at transformer 9 necessary for the proper working of track relays on track circuits of different lengths and characteristics.

I have referred to the fact that the variation 10 in track circuit current via winding 35 is reflected in the transmission circuit 37-38 synchronously and automatically by virtue of change in magnetic flux density in the magnetic circuit of inductive coupling transformer 34. This action will be more readily understood by referring to Fig. 3, wherein is represented what is known as a magnetization curve—the abscissa representing flux density and the ordinates representing current flow in 15 a winding surrounding the magnetic circuit—which shows graphically the comparative behavior of iron when under the influence of an electric current. Referring to Fig. 3 it will be evident that the greater the current flow 20 the greater the flux density and vice versa with uniform variation but this uniform variation only holds true under the knee K of the curve. Above the knee of the curve, it will be noted, a comparatively great increase 25 in current flow will be accompanied by only a small increase in flux density. In general, inductive coupling 34 is so designed that the current flow in the primary winding 35, when the track circuit is not occupied, produces 30 only a low flux density—consequently only a low induced power appears in the transmission circuit—and when the car-wheel shunt is at transformer 9 end of the track circuit the increase in current flow in winding 35 produces 35 a correspondingly greater flux density (but still under the knee of the curve) and consequently a greater induced power in the transmission circuit. The foregoing, of course, has reference to the operation of inductive coupling 34 and its influence on the indication system when propulsion current is not present in the track circuit to any appreciable degree.

Referring again to Fig. 3 it will be noted 50 that the magnetization curve indicates uniform variation under the knee of the curve and that a comparatively great increase in magnetizing current thereafter produces only a small change in flux density—in fact, as 55 illustrated, an increase of 100% in magnetizing current shows only about 30% increase in flux density, and as the induced power is due to the flux density and not to the magnetizing current it is apparent that variations in magnetization current above the knee of the curve 60 will not be reflected proportionately in the transmission circuit and therein lies the basis for the influences and effects of propulsion current flow in winding 35 on the indication system presently to be described.

Referring to Fig. 1, it will be observed that track rail 6 is connected permanently in multiple with track rail 7 at the relay end of the track section and also again at the transformer 9 end of the track section;—the multiple 70 at the relay end being via wires 19, 20, fuse 21 resistance 22 and winding 23 and at the transformer end via wires 10, 11, fuse 13, secondary winding of transformer 9 and resistance 12 with winding 35 in multiple. 75 Obviously, track rail 6 is not intended to carry any appreciable amount of propulsion current and resistances 12 and 22 are inserted in the respective paths to restrict the flow of propulsion (direct or alternating) current there- 80 in because an excessive flow would tend to magnetically saturate the track relay and track transformer 9 and cause heating and other obvious undesirable effects. Owing to the permanent multiple, just explained, some 85 propulsion return current does flow in winding 35 at any time a train motor is using power with the track section, illustrated, intervening between said train position and generator G—and the train, therefore, need not necessarily 90 be on a particular track section to cause propulsion current to flow via winding 35.

When the train enters the track section the train (car-wheels 43-43^a) provides a direct connection between rails 6 and 7 of considerably greater conductance than formerly existed and as a consequence track rail 6 is a correspondingly greater conducting path in multiple with track rail 7 and more propulsion return current flows in track rail 6 than 100 formerly. It will be obvious, that the relation of track rail 6, as a conducting path in multiple with track rail 7 is variable corresponding to the position (in the track section) of the train, track rail 6 being of proportionately greater multiple value when the train is at the relay end of the track section and of practically no value when the train is at the transformer 9 end of the track section—therefore more propulsion return current 110 flows via winding 35 when the train is at the first mentioned end of the track section and variably less of the propulsion current flows via winding 35 as the train proceeds through said track section under electric power. 115

The effect of direct current (propulsion) flowing with the alternating signaling current in the same circuit is to produce a bias—that is, the direct current which always flows in the same direction, at a time, may be said 120 to reinforce one-half of the alternating current wave and to suppress the other half of said wave. The actual fact is, that the direct current tends to permanently line up the flux of the magnetic circuit in one direction 125 so that the flux cannot respond to the alternating current signaling current wave and this is illustrated in Fig. 4, wherein a direct current (propulsion return current) of the value indicated is assumed to be flowing in 130

the circuit including winding 35, as hereinbefore explained, and in a direction to suppress the negative half of an alternating current wave. When such is the case, it is apparent that an alternating signaling current of any value present in the same circuit, because of an occupied track circuit, can only influence the flux of the magnetic circuit to the certain extent that the flux is not pre-influenced by the propulsion return current, so to speak. To illustrate the conditions in effect, a simple sine wave PP of the value indicated is shown (by dotted line) superposed on the direct current component. The flux wave resulting from the combining of the direct current and alternating current of these values is shown, as identified, and assumes this particular shape because of the fact that most of the alternating current flow in winding 35 does not affect the magnetization appreciably because at that point (at and above the knee of the magnetization curve) variation in current produces a comparatively small change in flux density.

Fig. 4 is intended to illustrate at the left end of the figure the proportionable values in effect with the train, now electrically propelled, entering the left end of the track section and under which condition the alternating signaling current flow through winding 35 would be a minimum (because of the track rail resistance included in the car-wheel shunt on transformer 9) and the propulsion direct current flow through winding 35 would be a maximum (because that is the time when the multiple value of the circuit via track rail 6, transformer 9 and winding 35 in multiple with track rail 7 is greatest). Fig. 4 at the right end is intended to illustrate the proportionable values in effect with the train, still electrically propelled, at the halfway point in the track circuit. It will be appreciated, of course, that, when the train arrives at the transformer 9 end of the track circuit the propulsion direct current will have practically disappeared and the alternating signaling current will have become of maximum value in which event the primary current, the flux wave and the induced current wave will be as described in connection with Fig. 2.

It will be noted that the component current due to the propulsion direct current at the left end of Fig. 4 substantially saturates the magnetic circuit up to the knee of the magnetization curve and the further increase of current flow due to the alternating signaling current acts to produce a ripple in the flux wave which ripple follows the A. C. wave in so far as the flux density permits and the flux wave is shown following only the lower end of wave PP at first, but, as the propulsion direct current component decreases (due to the train proceeding through the track circuit) gradually following more and more the wave shape of the alternating signaling cur-

rent until the flux follows the complete signaling current wave when the train is at the transformer 9 end of the track circuit.

As above explained it will be clear that the combination of the direct propulsion current and alternating signaling current in winding 35 acts to produce a unidirectional ripple effect on the flux wave of transformer 34 with maximum and minimum values in time relation corresponding to the period of the alternating current.

With a variable flux wave, generated according to propulsion direct current and alternating signaling current conditions in the track circuit, a basis is provided to generate a characteristic secondary current flow and wave BB Fig. 4 illustrates the wave shape of secondary current flow in the transmission circuit 37-38.

Referring to Fig. 4, it will be observed that the secondary current wave BB is shown to have O value at point R from which point the wave with a concave wave front indicates an increase in current flow to a certain positive value S corresponding to the density and rate of change of the flux at that time—from which point (S) the secondary current value (wave BB) recedes rapidly with a straight wave back to O value and rebuilds with a straight wave front to a certain value S¹ corresponding to the density and rate of change of the flux as before and then said secondary current value recedes with a concave wave back to O value at point R¹ and thereafter similarly with recurring cycles. That the positive wave front should be so shaped will be evident from the fact that at point R the flux, though at a maximum value, is at rest and as the cycle proceeds the value of flux is reduced at an increasing rate until the point S (wave BB) is reached. The flux wave rate of change then slows up rapidly thus accounting for the straight positive back of wave BB and as the flux wave rate of change comparatively rapidly increases until a point on the flux wave corresponding to point S¹ (wave BB) is reached it will be clear that the negative front of wave BB will be straight. Now, even though the value of flux is increasing, the rate of change is slower thus accounting for the concave negative back of wave BB.

As the value of the propulsion direct current component is decreased (as the train proceeds through the track circuit) the flux wave follows the alternating signaling current wave for a greater part of a cycle resulting in the positive wave fronts and negative wave backs of wave BB still concave but with a greater amplitude and with the positive wave backs and negative wave fronts of wave BB gradually assuming a convex form as is clearly indicated in the shape of wave BB at the right end of Fig. 4. It will be appreciated, of course, that as the direct current com-

ponent is reduced (due to the train reaching the transformer 9 end of the track circuit) the concave positive wave front and negative wave back will be replaced by the regular sine 5 wave shape and to all intents and purposes wave BB, of Fig. 4 will become a facsimile of wave BB of Fig. 2.

In the above description it was assumed that the propulsion direct current flow in 10 winding 35 was such as to reinforce the positive half of the alternating signaling current wave and in this event the secondary wave BB positive fronts and negative backs were suppressed but it will be appreciated that the 15 propulsion direct current flow, according to design, or the conditions of operation, may be used to reinforce the negative half of the alternating signaling current wave in which event the secondary wave BB negative fronts 20 and positive backs would be suppressed.

Referring now to the power wave CC Fig. 4—the corresponding points of which are line referenced to the flux wave and the induced current wave BB. It will be noted that, be- 25 cause of the direct current component of the current flow in winding 35, comparatively little influence of the alternating current component is reflected in the transmission circuit and with very little semblance of sine 30 wave shape. This is so because of the difference in fronts and backs of the induced current wave BB. As between points R and R¹ (wave BB) of recurring cycles, the periodicity of the alternating signaling current 35 (for this case 1/25 second) is maintained and the influence of the signaling current reflect- 40 ed is fractionally that of the negative half of the alternating current primary wave (when the train is entering the track section) and the power wave peaks (wave CC) occur 45 midway between points in the power wave CC corresponding to points R and R¹ of induced current wave BB. The lower the am- 50 plitude of the power wave CC the closer the power wave peaks of a given cycle appear together and the closer the power wave peaks of a given cycle occur the longer must be the period between the power waves of recurring cycles, all of which is clearly set forth in Fig. 4.

The long periods as between power waves of recurring cycles are essentially periods of substantially no power flow in the transmission circuit and hence no power input to the 55 indicating device—in this case lamp 42. This gives rise to a flicker condition of the illumination of lamp 42, the light and dark intervals of which vary according to the amount of propulsion direct current flow in 60 winding 35—the greater the amount of direct current the longer the dark interval so that the flicker indication of the illumination may be accepted as a comparative index as to the value of the direct current flow in winding 65 35, it being understood, that different pro-

portions of direct current and alternating current will act responsively in a manner which can readily be set forth in illustration and in practice as hereinbefore explained, having in mind, of course, that the greater 70 the alternating current value the sharper the peaks with a given direct current component. I desire it to be understood that I have, at times, arranged the design of the inductive coupling 34 so that with the presence of a 75 suitable amount of direct current flow in winding 35 the induced effects of the original alternating current wave A were, to all intents and purposes, practically entirely suppressed or annulled as long as the flow of 80 direct current in winding 35 persisted, which, of course, is due to saturation in the magnetization of inductive coupling 34. The terms suppressed, annulled and nullify, as used in the claims are to be understood as follows; 85 suppressed—meaning that if excess propul- 90 sion current is present when the train enters the track section the indication device will not inductively respond to whatever indica- 95 tion current is flowing in the track circuit because of saturation of inductive coupling 95 34 by the propulsion current; annulled and nullify—meaning that while the indication device may be responding to indication cur- 100 rent the appearance of an excess amount of propulsion current will act to cancel said indica- 105 tion effect.

The lamp indicator in being operative to differentiate, by uneven periods of illumination, as hereinbefore pointed out, is, therefore, a device responsively and sensitively operative on an unsymmetrical wave form.

Attention is directed to the fact that, in the description in connection with Fig. 2, it was explained that current wave A when the track circuit was not occupied did not induce a sufficient amount of current wave B (Fig. 2), in the circuit including winding 36 to even slightly illuminate lamp indicator 42 and that an increase in alternating current flow in primary winding 35 does provide increased induced current flow in the transmission circuit and consequently increased illumination of lamp 42. This, of course, is due to the increase in flux density which, with the cyclic frequency remaining unchanged, produces a more rapid rate of flux change, which, as is well understood in the art, accounts for the induced power in the secondary circuit. As is well understood, induction may be carried into effect by an increase in the flux density of the magnetic circuit, by increasing the cyclic frequency per unit of time or both and in practice I have, at times, arranged the design of inductive coupling 34 so as to provide that a given increase in direct current flow in winding 35 will convert the influence of a minimum alternating current flow (due to an unoccupied track section) in winding 35 into a ripple direct current the maximum and mini- 110 115 120 125 130

mum values of which correspond to the positive and negative maximum values of the original alternating current and thus generating a flux wave similarly as set forth in Fig.

5 4, in fact it is apparent that an actual decrease in alternating current flow in winding 35 (with the track circuit unoccupied) can take place and when reinforced by a suitable value of superposed direct current, an induced current wave BB (Fig. 4) would be produced which would possess the necessary characteristics to produce responsive synchronous illumination of indicator lamp 42. This gives rise to the fact, that the indication 15 device may act without any increase in the energy supply from transformer 9—all of which is due to the fact of the degree of magnetization of the magnetic circuit of inductive coupling 34 being changed by virtue of the 20 propulsion return current flow.

It has been explained, that the track rails are permanently connected in multiple, for the case illustrated, and therefore bear a certain shunt relation to each other. Now, if 25 said relation becomes disturbed, by virtue of defective bonding or cracked rail, the fact will be exhibited by the indicator device as follows: If the defect occurs in track rail 7 an additional proportion of propulsion return current flows via winding 35 and if the defect is in track rail 6 less than the normal amount of propulsion current flows via winding 35 and in addition the former characteristic value of car-wheel shunt variation would 30 be altered both of which produce correspondingly different effects in the indication system, all as hereinbefore pointed out, due to change in degree of magnetization of the iron core of inductive coupling 34.

40 I have explained that the circuit for the propulsion return current from motor 45 was via track rails 6 and 7 and that a portion of the return current flowed via winding 35. Now, in order that propulsion current may 45 flow through motor 45 and via winding 35, operating circuit controller 46 must be closed and since this controller, either directly or by means of master controller as is well known in the art, may be operated at will by the motorman and thus bring about a change in the 50 amount and duration of propulsion current flow in winding 35, and consequently in the induced current effects on the indicator device, it is readily apparent, that I have provided a system whereby the motorman, without removing his hand from the controller, without stopping the train, and from any 55 point in the track section, may communicate with the tower or other selected location of the indicator device, said communication being originated by the opening and closing of the motor operating circuit at the train carried circuit controller 46, as will be appreciated.

The several indications of lamp 42, for the case of the lamp dark with the track section 65 unoccupied, are as follows;

1. Section unoccupied—no illumination.

2. Train entering section—coasting—illumination of low value and steady character.

3. Train continues through section—coasting—increasing value of illumination of steady character and synchronous with train movement.

4. Train stops—the value of illumination 75 synchronously attained remains unchanged.

5. Train moves in opposite direction—coasting—the indications 1 to 4 appear in reverse order. That is, the lamp begins full illumination with the train entering the track 80 section.

6. Train entering section under D. C. electric motor power—illumination of low value but flickering character.

7. Train continues through section under 85 D. C. electric motor power—increased value of illumination of flickering character—the flicker gradually disappearing and the indication as in 3 gradually appearing.

8. Train starts coasting in section—flicker 90 disappears—thereafter as in 3.

9. Train coasting begins D. C. motor power operation—first indication as in 3 and thereafter as in 7.

10. Motorman communicating with dispatcher—a series of flicker and steady illumination according to prearranged code.

The flickering indications are of several values and characteristics according to the cycle of light and dark intervals;—that is, with a given cycle 1/10 of which is light and 9/10 dark a characteristic impression is formed which is materially different from a cycle 5/10 of which is light and 5/10 dark and in this manner comparative values of superposed direct current flow are readily discernible. In other words, the flicker is slow or fast. So also, given an alternating current wave the larger the current value the sharper the wave at its maximum point and the smaller the current value the flatter the wave at its maximum point with correspondingly different effects in combination with the direct current component, as will be evident by referring to the flux wave of Fig. 4.

When installed on railroads using direct current for propulsion purposes I prefer to use a frequency of alternating current not in excess of 60 cycles per second because the filament section of the lamp required to respond to power flow for light and dark intervals becomes too frail, but I desire it to be understood that when installed on railroads using alternating current for propulsion purposes a much higher frequency is perfectly feasible because of the node or beat frequency effect due to superposing an alternating current of one frequency on an alternating current of a

different frequency, as will presently be pointed out.

Referring to Fig. 5—I have shown a simple sine wave identified as 25 cycle propulsion current—and intended to illustrate the propulsion current flow (when a train is moving under A. C. electric motor power) in winding 35 of my system (when installed on A. C. electrified railroads using 25 cycle A. C. for propulsion purposes) under conditions previously explained for the case with D. C. propulsion. Wave AA represents the indication system alternating current flow (in this case 60 cycles) in winding 35 with the track section occupied. As illustrated the 25 cycle propulsion current is twice the value of the 60 cycle signal current and the influence of the two waves combined (identified as primary current) is to produce a flux wave (in 20 inductive coupling 34) tending to follow the 25 cycle periodicity but with harmonics due to the 60 cycle periodicity. However, owing to the saturation of inductive coupling 34, as hereinbefore explained, the peak points 25 of the combined primary current values are suppressed, on account of the flux density, and the secondary voltage wave (indicated) follows a shape of greatly different character than the primary current. This is so, 30 because at some points the 60 cycle component has operated to increase the rate of change in the flux and at other points the primary current is not reflected because of saturation of the magnetic circuit of inductive coupling 34.

At the bottom of Fig. 5, I have indicated the 25 cycle propulsion current component (above referred to) by dotted line and by the hatched area I have clearly shown the 40 beats which are the natural result of the sharp wave fronts and backs which are carried into the transmission circuit and in reference to which it is not believed that further description is necessary. Obviously, various values 45 of propulsion and signaling current will variably affect the value and periodicity of the beats and it is further pointed out that due to the propulsion current being alternating in character the indication system and lamp 50 42 will synchronously indicate train presence and movement without 60 cycle current flow in winding 35—but with reverse effect—that is, the train in moving from left to right 55 will cause a reduction in indication lamp 42 illumination.

The indications of the indication lamp 42, when installed on A. C. electrified railroads are substantially similar to those, as above set forth for D. C. electrified railroads, except 60 that, of course, 1st, the beat flicker would be substituted for the flicker due to the D. C. component, and 2nd, an additional indication in the form of a comparatively slow but uniform flicker (due to the 25 cycle propulsion

current alone) is developed. These different 65 types of flickers are brought about in the use of a comparatively thin indication lamp filament.

In the specific illustrations and descriptions herein, I have made use of simple sine 70 waves, but it will be understood that my invention is broadly adaptable for use and effective without regard to wave shape and I desire it to be understood that, while I have 75 illustrated and described the indication effects as appearing in the transmission circuit, it will be evident that whatever induced effects are produced in the transmission circuit will all be substantially carried through 80 to the indication lamp device 42, or other appropriate means.

At this time it is to be noted, that the alternating current of the indication system is substantially a carrier wave by means of 85 which a class of information is transmitted to the indication receiver device, either in modified or unmodified wave form—the modifications being due to the superposing of other currents, the effect of which is to produce unsymmetrical wave shapes.

It is specifically disclosed, herein, that the flow of propulsion return current, in the sectionalized track rail under the several conditions is responsible for the operation of my invention but it is also pointed out that the presence of all currents in suitable amounts will be indicated in my system, and I further desire it to be understood that my invention is not limited to the particular type of track circuit shown, as I have produced similar results with all types of alternating current track circuits, on electrified railroads, including those disclosed in my prior Patent No. 1,596,222 and my prior application Serial No. 33,731, with the obvious appropriate changes 100 which any person ordinarily skilled in the art would use to modify my invention, herein disclosed, and, therefore, I wish it to be understood that my disclosure herein is merely 105 illustrative and does not exhaust the various 110 embodiments which come very clearly and broadly within the spirit and scope of this invention.

Having thus described my invention, I claim and desire to secure by Letters Patent: 115

1. A train indication system, characterized by an indicating device responsive to signaling current and influenced by a current other than said signaling current, both currents flowing in the rails of a railway track, both 120 currents coating to indicate the presence and movement of an electrically propelled train on said railway track.

2. A train indication system including a track circuit and source of signal current, 125 characterized by an indicating device responsive to signaling current and influenced by a current other than said signaling current,

- both currents flowing in one of the rails of a railway track, said device adapted to comparatively indicate variable amounts of said other current.
5. 3. A train indication system including a track circuit and source of signal current, characterized by an indicating device responsive to a wave of signaling current and influenced by a current other than said signaling current, both currents flowing in the rails of a railway track, said other current modifying the character of said wave.
4. A train indication system including a track circuit and source of signal current, characterized by an indicating device responsive to signaling current and influenced by a current other than said signaling current, both currents flowing in the rails of a railway track, said other current modifying the wave form of said signaling current.
5. A train indication system including a track circuit and source of signal current, characterized by an indicating device responsive to signaling current and influenced by a current other than said signaling current, both currents flowing in the rails of a railway track, said other current modifying said signaling current to produce an unsymmetrical wave form of current.
30. 6. A train indication system including a track circuit and source of signal current, characterized by an indicating device responsive to signaling current and influenced by a return current other than said signaling current, both currents flowing in the rails of a railway track, said other current modifying said signaling current to produce an unsymmetrical wave form, said device sensitive to said unsymmetrical wave form.
40. 7. A train indication system including a track circuit and source of signal current, characterized by an indicating device responsive to signaling current and influenced by a current other than said signaling current, both currents flowing in the rails of a railway track, said other current modifying said signaling current to produce a characteristic current, said device sensitive to said characteristic current.
50. 8. A train indication system including a track circuit and source of signal current, characterized by an indicating device responsive to signaling current and influenced by a current other than said signaling current, both currents flowing in the rails of a railway track, said other current modifying said signaling current to inductively produce a characteristic wave, said device synchronously sensitive to said characteristic wave.
60. 9. A train indication system including a track circuit and source of signal current, characterized by an indicating device responsive to signaling current and influenced by a current other than said signaling current, said signaling current controlling said device,
- and an excess of said other current nullifying said control.
10. A train indication system including a track circuit and source of signal current, characterized by an indicating device responsive to signaling current and influenced by a return current other than said signaling current, an excess of said other current acting to suppress the response of said device to said signaling current.
11. A train indication system including a track circuit and source of signal current, characterized by an indicating device responsive to signaling current and influenced by a return current other than said signaling current, both currents controlled by train movement on a railway track, said signaling current controlling said device, and an excess of said other current nullifying the response of said device to said signaling current.
12. A train indication system including a track circuit and source of signal current, characterized by an indicating device responsive to signaling current and influenced by current other than said signaling current, both currents controlled by train movement on a railway track, said signaling current controlling said device, and an excess of said other current acting to suppress the response of said device to said signaling current.
13. A train indication system including a track circuit and source of signal current, characterized by an indicating device responsive to signaling current and influenced by a return current other than said signaling current, both currents controlled by train movement at any point on a railway track, said signaling current controlling said device, and an excess of said other current acting to nullify the response of said device to said signaling current.
14. A train indication system including a track circuit and source of signal current, characterized by an indicating device responsive to signaling current and influenced by a return current other than said signaling current, both currents controlled by train movement at any point on a railway track, said signaling current controlling said device, and an excess of said other current acting to suppress the response of said device to said signaling current.
15. A train indication system including a track circuit and source of signal current, characterized by an indicating device responsive to signaling current and influenced by a current other than said signaling current, both currents controlled by train movement at any point on a railway track, the combination of said currents acting to inductively produce a current of unsymmetrical phase relation, said device sensitive to said induced current.
16. A train indication system including a track circuit and source of signal current,

characterized by an indicating device responsive to signaling current and influenced by a current other than said signaling current, both currents controlled by train movement 5 at any point on a railway track, said other current also controlled by operable train carried means, said device sensitive to the operation of said means.

17. A train indication system including a 10 track circuit and source of signal current, characterized by an indication device responsive to signaling current and influenced by current other than said signaling current, both currents controlled by train movement 15 at any point on a railway track, said other current also controlled by operable train carried means, said means in combination with said other current acting to nullify the response of said device to said signaling current.

20. 18. A train indication system including a track circuit and source of signal current, characterized by an indication device responsive to signaling current and influenced by current other than said signaling current, 25 both currents controlled by train movement at any point on a railway track, said other current also controlled by operable train carried means, said means in combination with said other current acting to suppress the 30 response of said device to said signaling current.

19. A train indication system including a track circuit and source of signal current, characterized by an indication device responsive to signaling current and influenced by current other than said signaling current, both currents controlled by train movement 35 at any point on a railway track, said other current also controlled by operable train carried means, said means in combination with said other current acting to synchronously influence said indication device.

20. The invention set forth in claim 2, distinguished by an inductive coupling included 45 in the circuit which includes the track rails.

21. The invention set forth in claim 5, distinguished by an inductive coupling in multiple with a resistance and included in the circuit which includes the track rails.

50. 22. The invention set forth in claim 6, distinguished by said device being inductively coupled to the circuit in which both said signaling and return currents flow.

23. The invention set forth in claim 10, distinguished by said device being inductively coupled to the circuit in which both said signaling and return currents flow.

60. 24. The invention set forth in claim 11, distinguished by said device being inductively coupled to the circuit in which both said signaling and return currents flow.

25. The invention set forth in claim 13, distinguished by said device being inductively coupled to the circuit in which both said signaling and return currents flow.

26. The invention set forth in claim 14, distinguished by said device being inductively coupled to the circuit in which both said signaling and return currents flow.

27. The invention set forth in claim 16, distinguished by said device being inductively coupled to the circuit in which both said signaling and said other currents flow and controlled by the train carried means.

28. The invention set forth in claim 17, distinguished by said device being inductively coupled to the circuit in which both said signaling and said other currents flow and controlled by the train carried means.

29. The invention set forth in claim 18, distinguished by said device being inductively coupled to the circuit in which both said signaling and said other currents flow and controlled by the train carried means.

30. In a railway traffic controlling system, 85 a track and circuit adapted for the operation of electrically propelled trains, a source of energy therefor, a train including a controller adapted to receive and utilize said energy, another source of energy impressed 90 on the track rails, an inductive coupling adapted to be influenced by both sources of energy, and an indication device responsive to the current flow in said inductive coupling.

31. The invention set forth in claim 30, 95 with the inductive coupling connected in series with the second source of energy.

32. The invention set forth in claim 30, 100 with the inductive coupling in multiple with a resistance and connected in series with the second source of energy.

33. The invention set forth in claim 30, 105 with the indication device synchronously responsive to current flow from the second source and sensitive to the operation of the controller.

34. The invention set forth in claim 30, 110 with the indication device operative to detect defects in the propulsion return current system.

35. The invention set forth in claim 30, 115 with the indication device operative to detect energy flow in the propulsion current system independent of increase in the flow of energy from the second source.

36. The invention set forth in claim 30, 120 with an electric lamp acting as the indication device and operative to characteristically indicate variations in the energy flow from either of said sources.

37. The invention set forth in claim 30, 125 with an electric lamp acting as the indication device and operative to characteristically indicate variations in the energy flow through one of the track rails from the second source and various combinations of energy flow from both sources.

38. The invention set forth in claim 30, 130 with an electric lamp acting as the indication device and operative to indicate when said

train is being operated by energy from the first source and when said train is coasting.

39. The invention set forth in claim 30, with an electric lamp acting as the indication device and operative to characteristically indicate the movement of the train on the track rails with and without energy from the first source.

40. In a train controlled railway signal system, a track circuit including a source of alternating current energy, an indicating device incorporated in said track circuit, an electrically propelled car, a propulsion current system and a car carried circuit controller therefor, said indicating device responsive to said alternating current flow in said track circuit due to a car thereon, and means including said propulsion current said car and said circuit controller for suppressing the response of said device to said alternating current track circuit current flow.

41. In a train controlled railway signal system, a track circuit including a source of alternating current energy, an indicating device incorporated in said track circuit, an electrically propelled car, a propulsion current system and a car carried circuit controller therefor, said indicating device responsive to said alternating current flow in said track circuit due to a car thereon, and means including said propulsion current said car and said circuit controller acting at times to nullify the response of said device to said alternating current track circuit current flow.

42. In a train controlled railway signal system, a track circuit including a source of alternating current energy, an indicating device incorporated in said track circuit, an electrically propelled car, a propulsion current system and a car carried circuit controller therefor, said indicating device inoperative to alternating current flow alone in said track circuit, and means including said propulsion current said car and said circuit controller for increasing the current flow to said device.

43. In a train controlled railway signal system, a track circuit including a source of alternating current energy, an indicating device connected in series in the energy supply to said track circuit, an electrically propelled car, a propulsion current system and a car carried circuit controller therefor, said indicating device responsive to alternating current flow in said track circuit due to a car thereon, and means including said propulsion current said car and said circuit controller for characteristically influencing the response of said device to said alternating current track circuit current flow.

44. In a train controlled railway signal system, a track section, a track circuit including both rails of said track section, a source of energy including the secondary winding of a transformer for supplying current to said track circuit, an indicating device connected in

series with the energy supply to said track circuit and controlled by car wheels on said track section, a car equipped with an electric motor for propelling said car, a source of propulsion current, a transmission circuit including a third rail sliding contact and the track rails of said track circuit for supplying said propulsion current to said motor, and a car-carried controller for controlling said transmission circuit, said indicating device responsive to said track circuit current alone and to a predetermined amount of propulsion current in combination with said track circuit current but non-responsive to a greater amount of said propulsion current.

45. In a train controlled railway signal system, a track circuit including a source of alternating current supply connected to one end of said track circuit, an indicating device connected in series with and responsive to said current supply to said track circuit and adapted to be controlled by a car on said track circuit, a car equipped with an electric propelling motor for propelling said car, a source of propulsion current, a transmission circuit including a third rail a sliding contact and the track rails of said track circuit for supplying said propulsion current to said motor, and a car-carried circuit controller for controlling the current flow in said transmission circuit, said circuit controller in combination with said propulsion current also acting to influence the control of said indicating device by said car on said track circuit.

46. In a railway train indicating system, a source of propulsion current, a transmission circuit comprised of a third rail and track rail return system, a train including an electric motor adapted to propel said train, said train at times receiving propulsion current through said transmission circuit, a car-carried controller for controlling the propulsion current flow in said transmission circuit, an alternating current track circuit including said track rail and having a transformer source of energy at one end of said track circuit, a primary winding of a second transformer connected in series with the energy supply to said track circuit, a primary winding of a third transformer connected to the secondary of the second transformer, and an indicating lamp connected to the secondary of the third transformer.

47. The invention set forth in claim 46 with a track relay connected to the track rails at the opposite end of the track circuit, said track relay controlling a block signal system.

48. The method of controlling alternating current signal circuits on an electrically propelled railway system using the track rails for the propulsion return current associated with an alternating current signaling system; which consists in causing a part of the propulsion return current to flow through the track rails in common with the signal current when the

track section is occupied by a car; and causing an excess of said propulsion return current to act to suppress the normal response of a signal device to said signal current, substantially as described.

49. The method of controlling alternating current signal circuits, on an electrically propelled railway system using the track rails for the propulsion return current associated with an alternating current signaling system; which consists in causing a part of the propulsion return current to flow through the track rails in common with the signal current when the track section is occupied by a car; and causing an excess of said propulsion current to act to nullify the normal response of a signal device to said signal current, substantially as described.

50. The method of controlling alternating current signal circuits, on an electrically propelled railway system using the track rails for the propulsion return current associated with an alternating current signaling system; which consists in causing a part of the propulsion return current to flow through the track rails in common with the signal current; and causing an increase of said propulsion current to act to increase the flow of alternating current energy to a signal device, substantially as described.

51. The method of controlling alternating current signal circuits, on an electrically propelled railway system using the track rails for the propulsion return current associated with an alternating current signaling system; which consists in causing a part of the propulsion current to flow through the track rails in common with the signal current when the track section is occupied by an electrically propelled car; and causing the combination of propulsion return current and signal current to synchronously operate an indicating device to show when a car is being electrically propelled, substantially as described.

52. The method of controlling alternating current signal circuits, on an electrically propelled railway system using the track rails for the propulsion return current associated with an alternating current signaling system; which consists in causing a part of the propelling current to flow in a circuit with said signaling current when the track section is occupied by a car; and causing said propelling current to modify the signaling current to produce a characteristic pulsating current; for operating a signal device sensitive to said alternating current and sensitive to said pulsating current.

53. The method of indicating the movement of an electrically propelled train on a railway track, associated with an alternating current signaling system; which consists in causing a part of the propulsion return current to flow in a circuit with said signaling current; and causing said propulsion return current to produce a pulsating current proportional to the position of the train on said track, for synchronously operating an indicating device.

54. In a railway traffic controlling system, a track circuit including a source of energy, an indication transmitter included in the energy supply to said track circuit, an additional source of energy at times flowing in said track circuit, said transmitter responsive to the current flow from both sources in said track circuit, and an indication receiver device synchronously responsive to induced current flow from said transmitter and sensitive to indicate the presence of either or both sources of energy in the track circuit.

55. The invention set forth in claim 54, said indication device inductively coupled to said transmitter.

56. The invention set forth in claim 54, said indication device inductively coupled to said transmitter, said device synchronously responsive to beat frequency current flow in the transmitter.

57. The invention set forth in claim 54, said indication device inductively coupled to said transmitter, said device synchronously sensitively responsive to current flow in the transmitter from either source independently of the other source.

58. The invention set forth in claim 54, said indication device inductively coupled to said transmitter, said device synchronously indicating the presence and movement of a train on said track in response to induced current flow from either or both of said sources.

Signed at Brooklyn, in the county of Kings, and State of New York, this 30th day of June, A. D. 1925.

GILBERT C. WHITNEY.
